UNITED STATES PATENT OFFICE

PAUL B. TAYLOR, OF PONTIAC, MICHIGAN, ASSIGNOR TO GENERAL MOTORS CORPORATION, OF DETROIT, MICHIGAN, A CORPORATION OF DELAWARE

CRANK-CASE VENTILATION

Application filed March 10, 1927. Serial No. 174,389.

This invention relates to crank case ventilating systems of the type disclosed in the application of W. S. Cochrane, Ser. No. 112,625, filed May 29th, 1926. In that application there is disclosed a fan blast operated ejector arranged to produce an aspirating action on a conduit leading to the crank case, the conduit preferably being a branch of the usual oil filler tube. By this means the gases and vapors, principally water vapor and fuel components, which have found their way into the crank case from the combustion chamber and which, if permitted to remain, would condense and dilute the engine oil are drawn out of the crank case for discharge at any suitable place e. g. under the car, where the odors cannot reach the passengers. The vapors thus removed are replaced by clean air entering the crank case at a point remote from the aspirator.

One feature of my invention consists in combining with an aspirator of this type a separator to remove particles of oil from the issuing vapors prior to their passage into the ejector to conserve the engine oil supply. The separator is preferably of the centrifugal type to reduce to a minimum interference with air flow. I have likewise so arranged my separator that the recovered oil drains back to the crank case through the conduit from which the vapors emerge.

Another feature of my invention consists of an improved construction of screened cap for the inlet opening through which clean air is supplied to the crank case.

In the drawings Figure 1 is a side elevation of an automobile engine to which my ventilating system is shown applied, the cap for the air inlet opening being shown in section.

Figure 2 is a front elevation with parts broken away.

Figure 3 is a section on line 3—3 of Figure 1.

Figure 4 is a vertical section through a modified form of cap or shroud for the clean air inlet.

The reference character 2 indicates an automobile engine of conventional type provided with a crank case 4 and a cooling fan

6. 8 indicates the oil filler tube which adjacent its base is provided with a branch 10 communicating tangentially with a cylindrical casing 12. An ejector 14 extends centrally through the casing. The ejector is discontinuous comprising a funnel member 16 adapted to receive air from the fan 6, the funnel terminating adjacent pipe 18 extending through the rear wall of the casing 12 and discharging preferably below the usual drip pan so that unpleasant odors of the exhaust do not reach the occupants of the car. The casing 12 is tilted rearwardly as shown to drain recovered oil back into the crank case.

At 20 I have shown an air inlet conduit, preferably spaced the length of the engine from the outlet conduit so as to insure a thorough mixing of air with the crank case contents. To the upper end of the conduit is secured a stamping 32, on which is mounted by means of bolt 34, a cap or hood 36 having a depending skirt 38 overlying the conduit 20. To the skirt 38 is secured in spaced relation by means of suitable arms, an annulus 40 surrounding the air inlet conduit. Between the annulus and the cap is arranged a screen 42.

With the described construction air entering the crank case through the inlet 20 is drawn to the forward end of the engine by the aspirating effect of the fan blast, and, passing tangentially into the casing 12, the heavy particles of oil are thrown outwardly, collecting upon the casing wall, and drain back to the crank case through the same passages 10 and 8, through which air leaves the crank case. The air from the crank case passes downwardly through tube 18 and is discharged under the engine.

In Figure 4 I have shown a slightly modified form of air inlet cap, this consisting of a screen carrying member 44 clamped to a conduit 46 communicating with the crank case, by means of bolt 48 and cap 50. The member 44 carries a depending skirt 52. In this and the other form of inlet, the skirt serves to exclude large particles of dust and dirt while the screen removes the finer particles by filtration. As the air enters the

crank case at relatively low velocity cleaning by this simple means is quite effective.

In the following claims I have referred to the gases withdrawn from the crank case as "air" in the interests of simplicity in terminology but it is to be understood that I have reference to the complex gaseous mixture present in the crank case.

This invention is susceptible of considerable modification as suggested by the omission of various illustrated elements in the structures called for by the claims.

I claim:

1. An engine having a crankcase, a port for admitting air to the crankcase, a port for the discharge of air from the crankcase, a cylindrical casing, said last named port communicating tangentially with said casing at one end thereof, and a blast operated injector extending centrally through the casing and communicating with the interior thereof at the other end of the casing.
2. The combination of an engine having a crankcase provided with an air inlet, and an air outlet, a cylindrical casing, said outlet communicating with the casing at one end thereof, said casing having an axial air outlet tube extending into the casing, and an injector extending into the casing from the opposite end thereof and having its inner end spaced from the outlet to induce flow of vapors from the crankcase through the casing and into the outlet tube.
3. The combination of an engine having a crankcase provided with an air inlet, an inclined cylindrical casing having at its lower end a tangential air inlet connected to the crankcase and serving as the crankcase outlet, an axial air outlet extending into the casing, and an injector extending into the other end of the casing in axial alinement with said axial air outlet but spaced therefrom to provide an aspirator to remove vapors from the crankcase.
4. The combination of a cylindrical casing having at one end a tangential vapor inlet, said casing being provided with a vapor discharge tube extending in an axial direction into the casing, an injector extending into the casing from the opposite end and having its inner end spaced from the inner end of the vapor outlet tube to induce a circulation of vapors through the casing and out the vapor outlet, said vapors performing a whirling motion in their travel through the casing to effect separation of foreign particles by centrifugal action.

In testimony whereof I affix my signature.
PAUL B. TAYLOR.
